UNITED STATES PATENT OFFICE.

EDITH A. FAUNT, OF VANCOUVER, BRITISH COLUMBIA, CANADA.

MUSIC NOTATION.

Application filed March 4, 1922. Serial No. 541,097.

To all whom it may concern:

Be it known that I, EDITH A. FAUNT, citizen of the Dominion of Canada, residing at Vancouver, in the Province of British Columbia, Canada, have invented certain new and useful Improvements in Music Notation, of which the following is a specification.

My invention relates to a music notation, 10 the main object of which is to represent the harmonic relationship of the various pitches in a simpler and more comprehensive manner than has hitherto been done, and to introduce features which will facilitate the 15 sightreading of vocal and instrumental music by both beginners and advanced musicians.

This object is achieved by the introduction 20 of a series of vocalizing syllables, and by substituting new forms where necessary. This is done in such a manner as to effect the transition from the existing to the new notation without much mental re-adjustment on the part of the performer or disruption 25 of the music printing trade.

25 The following specification shows the application of the notation to the piano, and in one or two instances, to vocal music, although the advantages indicated apply in equal measure to players of any instrument 30 for which the existing notation is or may be used.

Time, and any other features of the existing notation not modified to form a part of my invention, are retained and used as heretofore.

35 Fig. 1 shows oval noteheads with insets indicating white keys which have harmonic names other than natural.

Fig. 2 shows diamond shaped noteheads 40 without and with inset, indicating black key sharps and double sharps respectively.

Fig. 3 shows how black key flats and double flats are indicated by rectangular noteheads without and with inset respectively.

45 Fig. 4 shows modifications of the existing staff to meet my requirements.

Fig. 5 shows my form of treble clef placed on the treble staff, followed by combined 50 key and time signatures.

Figure 6 shows my form of separate or complete time signature placed on the bass staff, also my form of F clef and the signature for key B natural.

55 Fig. 7 shows a series of rest symbols.

Fig. 8 shows a G (upper) and F (lower)

staff placed over the diagram of a keyboard octave to show: firstly, the indication of sharps, flats, and naturals by means of a distinctive outline for each; secondly, the 60 vocalizing syllable for each pitch.

Fig. 9 shows on a keyboard octave my method (upper) of indicating what may be termed white key sharps and flats, compared with the existing method.

Fig. 10 illustrates the adoption of the same principle in the representation of double sharps.

Fig. 11 shows my method of indicating double flats (upper) compared with the 70 existing method (lower).

Fig. 12 illustrates how my notation (upper line) eliminates the necessity for accidentals, thus gaining in neatness over the 75 existing method.

Fig. 13 illustrates: firstly, the elimination of calculation before striking double flats; secondly, the advantage of the modified staff for naming pitches several leger lines up or down; thirdly, the elimination of the necessity for the memorization of the sharps or flats of the key.

Fig. 14 shows the notation applied to a chord and single note passages where sharps and double sharps are prevalent, to illustrate 85 the simplicity brought about both in appearance and mental reaction, by the use of my notation.

The oval outline (2) now in use is retained to indicate white keys only. In Fig. 90 1 four insets are introduced (3), (4), (5), (6), these being white on black, or black on white, as required. All noteheads containing insets are named from the pitch above or below in accordance with the interpretation 95 of the inset.

The diamond inset (3) indicates that the pitch shown is to be named the sharp of the pitch one semitone below. This occurs only on pitches C and F when the harmonic 100 names are B sharp and E sharp respectively. (Fig. 9.) The rectangular inset (4) is used on pitches E and B to indicate F flat and C flat respectively. See Fig. 9.

The vertical bar inset (5) indicates double 105 sharp. For example: An oval notehead with a vertical bar insect on pitch G (see 21 in Fig. 10) is named F double sharp (22 in Fig. 10). By thus placing a distinctive notehead on the pitch to be played, the calculation of a tone up, by the player, is eliminated. This is of great advantage to the 110

sight reader, while the drawback to the harmony student (of having to make a calculation for the name) is very slight in comparison, since speed is by no means so important to him.

The same principle is followed with double flats, which are indicated by an oblique bar inset (6) running downward from left to right at an angle of thirty degrees with the horizontal. This angle, though not essential, has been chosen as the most practical, since it can readily be obtained from the thirty set-square. Fig. 11 shows the representation of each double flat on the staff.

15 Sharps and double sharps played on black keys are indicated by the diamond outline shown in Fig. 2, single sharps having no inset as shown on the left, and double sharps having the characteristic vertical bar inset. 20 The latter form of double sharp could only occur on pitches F and C when indicating E double sharp and B double sharp respectively (23 in Fig. 10).

Black-key flats and double flats are indicated by the rectangular outline shown in Fig. 3, the oblique bar inset shown on the right distinguishing the double flat from the single (left). This form of double flat is used on pitches B and E to indicate C double flat and F double flat respectively, as shown in Fig. 11 (24).

Since only a small percentage of white-key and double sharps and flats are used in music, the vast majority of music would require only the three outlines, void of insets, as shown in Fig. 8. The gain in neatness and clearness resulting from the elimination of accidentals is illustrated in Fig. 12, which shows a passage from "Anitra's Dance" 40 written in the new (upper) and existing (lower) notations. A further advantage is the elimination of memory work, since the sharps or flats of the key are indicated wherever they occur. Comparison in Fig. 45 13 of the new (upper) with the existing notation illustrates this advantage. Thirteen notes are shown flat by means of the rectangular outline in the new notation, whereas in the existing notation the performer 50 must depend entirely on memory to play these as flats. The first five notes of the same passage demonstrates the advantage of indicating the pitch to be played where double and white-key flats occur. Similarly, 55 Fig. 14 shows the advantage of my notation for the indication of single (28), white-key (29), and double (30) sharps.

The oval noteheads may vary in size and in the proportion one diameter bears to the other in exactly the same way that noteheads vary in the existing notation, though a proportion of four units to seven is suggested as the most satisfactory to maintain a uniform appearance with the diamond and rectangular forms adopted. The adjacent

angles of the diamond form are sixty and one hundred and twenty degrees respectively, while the adjacent sides of the rectangular form bear the proportion of four to seven units. Notehead forms other than 70 those indicated may be used without departure from my invention.

In order to further eliminate all unnecessary memory work, the existing staff has been modified thus:

75 In every E and F space (7) a dotted line (8) is placed adjacent to the lines F and E respectively. A broken line (9) is similarly used in spaces B and C (10), this line being adjacent to the lines C and B respectively. 80 This modified form of staff has the following advantages over the existing one:

It eliminates the necessity for clef signatures, since the appearance of the staff is a sufficient and continuous indication as to 85 whether the treble or bass clef is being used. (A change of clef is shown half way through Fig. 7.) This continuous indication is of great advantage to the sight reader, since he is no longer dependent on 90 a sign placed at one point, which is liable to be overlooked.

The distinctive dotted and broken lines readily fix the location of E, F, B, and C in the mind of the learner, from which the 95 other three pitches can readily be identified, even when several leger lines are used.

These lines indicate where the semitones occur on the staff, corresponding with the pairs of white keys on the keyboard. This 100 alone is of considerable advantage to the beginner.

Although I am of the opinion that the clef lines of the treble and bass clef are sufficiently distinctive without any indication at the beginning, it may be advisable to adopt clef signs. If such are considered necessary I propose the forms G and F shown in Figs. 5 and 6 respectively. A necessary feature 105 of these is that the cross bars (11) and (14) are placed on the G and F lines respectively, as a ready indication of the pitches from which these signs take their names.

Since the introduction of distinct forms 110 of noteheads eliminates the necessity for key signatures, the tonic alone (12), (25), (27), (28), is indicated, for ready reference. The note value used to show the tonic serves also to indicate the beat unit, and is followed by a numeral indicating 115 the number of beats in a measure. This combined time and key signature (12 and 13) simplifies the work of the young beginner. A separate and complete time signature is shown (15) in Figure 6 and in Figure 12, wherein the note-value shown indicates the value of each beat, while the 120 numeral tells the number of beats in a measure.

130 The series of mnemonic rests shown in

Fig. 7 are simple enough for the young learner to reproduce. The measure rest (16) consists of a miniature measure bounded by the second and fourth lines of the staff, 5 the dimension proportions corresponding with those of the "flat" noteheads, with the long dimension parallel to the staff lines.

Though the note rests are shown with varying proportions to demonstrate that the 10 one of four to seven is not indispensable, this is suggested to be uniform with the noteheads adopted. With all rest symbols other than that for the whole measure the long dimension runs at right angles to the 15 staff lines to prevent confusion with noteheads indicating flats. Each possesses some particular feature by which to identify it with the note value it represents.

The whole note rest (17) is, like the whole 20 note itself, indicated by an outline merely. The half note rest (18) is indicated by inserting the stem of the half note as a vertical line passing down the centre. The distinctive feature of the quarter note, solid 25 black, is repeated in the quarter note rest (19), while for the eighth, sixteenth, thirty-secondth, and sixty-fourth note rests the number of note hooks is indicated by the insertion of the corresponding numeral, 30 since hooks are the distinguishing features of these note values. For example: a sixteenth note has two hooks, therefore the sixteenth-note rest (20) has the numeral 2 inserted as its distinguishing feature. Fig. 35 14 (31) illustratively shows the application of the eighth-note rest.

Another feature of my invention is the compilation of a series of vocalizing syllables (Fig. 8) in which the initial letters 40 correspond to the pitch names where these are consonants. The vowel sound varies with the harmonic name indicated by the outline. Naturals (oval outline) are sung to the vowel sound EE, sharps (diamond outline) to the sound AW, and flats (rectangular outline) to OO. This does not preclude the use of other vowel sounds if found more practical. These have been chosen to avoid confusion with each other 45 through faulty enunciation, and because EE suggests itself as most suitable for the naturals, since five out of the seven pitch names already possess this vowel sound.

Practically all authorities on voice production advocate the use of an introductory consonant for practice work by beginners, and since these syllables are designed with the needs of school music well in view, M 50 and L are used as introductory consonants for pitches E and A respectively. Thus the chromatic scale transposed into its vocalizing syllables becomes: ascending (that is, using sharps), as in the upper line of Fig. 8; cee, caw, dee, daw, mee, fee, faw, gee, 55 gaw, lee, law, bee, cee; descending (us-

ing flats) as in the lower line of Fig. 8, reading from right to left; cee, bee 70 boo, lee, loo, gee, goo, fee, mee, moo, dee, doo, cee. Ultimately, for practical purposes, only the vowel sounds for sharps and flats need be inserted (Fig. 12), the omission of a vowel sound indicating EE. A cedilla and small "j" are shown placed 75 under the c and g respectively when these are followed by "a" or "o" to indicate the soft sound of the letters is to be retained.

I am aware that a series of syllables is at present in use for vocalizing purposes but experience has proved these to be unsatisfactory when applied to staff notation, especially where accidentals and changes of key occur. Continual practice with my series of syllables would make the reading of melody habitual, and tend to develop a 80 sense of absolute pitch, which the tonic sol-fa movable doh system, now in use, tends to destroy.

I am also aware that suggestions have been made for a staff representing in one way or another, the appearance of the piano keyboard, but such suggestions have been quite distinct from the plan of representation disclosed herein, and fail to offer immediate advantages to both learner and advanced player. I am aware that a variety of noteheads has been suggested, but in no case have the needs of the harmony student been satisfactorily met without placing the performer, and particularly the sight reader, 90 at a great disadvantage through multiplicity of signs, whereas my notation indicates the exact pitch by locating one of three outlines on the staff, insets indicating modifications for pitch of the naturals to indicate flats or sharps.

Still further I am aware that a system of notation has been suggested based upon the mechanical peculiarities of the type of instrument, both as to staff and form of noteheads, but such a notation differs fundamentally from both mine and the existing one to such an extent as to render it impracticable. Moreover, such a notation makes no provision for the needs of the harmony student.

I claim:

1. In musical notation, a blank, having thereon the customary staff, using leger lines where necessary, note-heads having a definite outline indicating the character of the piano key (the white keys, the black sharp keys and the black flat keys), said note-heads having an inset indicating the name of the note.

2. In a musical notation, a blank, having thereon the customary staff, using leger lines where necessary, a distinctively different line adjacent to the E and F lines and in the E and F spaces of the staff, and a different line adjacent to the B and C lines and in the

- B and C spaces of the staff indicating an interval of one semi-tone between the natural in the space in which the distinctive line occurs, and the natural on the line to which the said distinctive line is adjacent.
3. In a musical notation, a blank, having thereon the customary staff, using leger lines where necessary, clef signatures consisting of the letters G and F, wherein the lower horizontal of the G is on the G line of the staff and the upper horizontal of the F is on the F line of the staff, said horizontals being duly emphasized.
4. In musical notation, a blank, having thereon the customary staff, using leger lines where necessary, a key signature consisting of a note-head located on the line or in the space of the tonic, indicating by its form whether the tonic is a sharp, flat or natural.
5. In musical notation, a blank, having thereon the customary staff, using leger lines where necessary, a key signature consisting of a note-head located on the line or in the space of the tonic, indicating by its form whether the tonic is a sharp, flat or natural and indicating by its note value the beat unit.
6. In musical notation, a blank, having thereon the customary staff, using leger lines where necessary, noteheads of distinctive outline that indicate the white keys of the piano, other note heads of distinctive outline that indicate the black piano-keys when termed sharps, and other note heads of further distinctive outline that indicate the black piano-keys when termed flats.
7. In musical notation, a blank, having thereon the customary staff, using leger lines where necessary, a time signature consisting of a note-value indicating the beat-unit below a numeral indicating the number of beats in a measure.
8. In musical notation, a blank, having thereon the customary staff, using leger lines where necessary, syllabic names adjacent to the notes, wherein the initial letters of the syllables correspond to the letter-names of the pitches where the same are consonants.
9. In musical notation, a blank, having thereon the customary staff, using leger lines where necessary, syllabic names adjacent to the notes, wherein the vowel sound varies to indicate the modifications for pitch of the naturals.
10. In musical notation, a blank, having thereon the usual staff, using leger lines where necessary, of a mnemonic representation of a measure placed on the staff, indicating a rest for one measure.
11. In musical notation, a blank, having thereon the customary staff, using leger lines where necessary, note rests in which a distinguishing feature of mnemonic or numeric type, within a distinctive outline, represents the note-value replaced.
12. In musical notation, wherein is provided a blank, having thereon the customary staff, using leger lines where necessary, combined with a distinctively different line adjacent to the E and F lines in the E and F spaces of the existing staff, and a further distinctive line adjacent to the B and C lines in the B and C spaces of existing staff, G and F clef signatures consisting of the letters G and F, the lower horizontal of the G being on the G line and the upper horizontal of the F being on the F line, a key signature consisting of a note-head, located on the line or in the space of the tonic, indicating by its form whether the tonic is a sharp, flat or natural and indicating by its note value the beat unit, and note-heads of three distinctive outlines, one of which indicates the white piano-keys, another the black piano-keys when termed sharps, and a third the black piano-keys when termed flats.
13. In musical notation, wherein is provided a blank, having thereon the customary staff, using leger lines where necessary, combined with a distinctively different line adjacent to the E and F lines in the E and F spaces of the existing staff, and a further distinctive line adjacent to the B and C lines in the B and C spaces of existing staff, G and F clef signatures consisting of the letters G and F, the lower horizontal of the G being on the G line and the upper horizontal of the F being on the F line, a key signature consisting of a note-head, located on the line or in the space of the tonic, indicating by its form whether the tonic is a sharp, flat or natural and indicating by its note value the beat unit, and note-heads of three distinctive outlines, one of which indicates the white keys of the piano, another the black piano-keys when termed sharps, and the third the black piano-keys when termed flats.
14. In musical notation, wherein is provided a blank, having thereon the customary staff, using leger lines where necessary, combined with a distinctively different line adjacent to the E and F lines in the E and F spaces of the existing staff, and a further distinctive line adjacent to the B and C lines in the B and C spaces of existing staff, G and F clef signatures consisting of the letters G and F, the lower horizontal of the G being on the G line and the upper horizontal of the F being on the F line, a key signature consisting of a note-head, located on the line or in the space of the tonic, indicating by its form whether the tonic is a sharp, flat or natural and indicating by its note value the beat unit, and note-heads of three distinctive outlines, one of which indicates the white piano-keys, another the black piano-keys when termed sharps, and the third the black piano-keys when termed flats.

- black piano-keys when termed sharps, and the third the black piano-keys when termed flats, said note heads having insets indicating the modifications in pitch of an adjacent 5 note in the natural scale, and syllabic names adjacent to the notes wherein the initial consonant of the syllable is the letter-name of the pitch where the said letter-name is a consonant.
- 10 15. In musical notation, a blank, having thereon the customary staff, using leger lines where necessary, distinctively different lines adjacent to the E and F lines in the E and F spaces and adjacent to the B and C lines 15 in the B and C spaces, clef signatures, consisting of the letters G and F, the lower horizontal of the G being on the G line of the staff and the upper horizontal of the F being on the F line of the staff, three sets of note-heads of distinctive outline, one indicating the white piano-keys, another the black piano-keys when termed sharps, and the third the black piano-keys when termed flats, certain of the said note heads having insets indicating the modifications in pitch 20 of an adjacent note in the natural scale. 25
16. In musical notation, a blank, having thereon the customary staff, using leger lines where necessary, note heads having distinctive outlines indicating the character of the piano-key to be struck, as: white key, black key termed sharp, black key termed flat, said note heads having an inset to indicate the theoretical name of the pitch in accordance 30 with the rules of harmony. 35

In testimony whereof I affix my signature.

EDITH A. FAUNT.
